Primary Examiner — Catherine A Tuttle

(57) **CLAIM**

The ornamental design for a toilet hoop, as shown and described.

DESCRIPTION

FIG. 1 is a perspective view of a toilet hoop showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a left bottom view thereof.

The netting shown in broken lines forms no part of the claimed design.
